UNITED STATES PATENT OFFICE.

HERMAN H. KEMPF, OF BROOKLYN, NEW YORK, ASSIGNOR TO LEO SCHLESINGER, OF NEW YORK, N. Y.

TOY GUN.

1,249,114.

Specification of Letters Patent.

Patented Dec. 4, 1917.

Application filed March 16, 1916. Serial No. 84,512.

To all whom it may concern:

Be it known that I, HERMAN H. KEMPF, a citizen of the United States, and a resident of the borough of Brooklyn, county of 5 Kings, and State of New York, have invented certain new and useful Improvements in Toy Guns, of which the following is a specification.

My invention relates to toy guns, preferably of the type which fires a projectile, although certain of the features of my invention are not limited to a gun of this particular type.

One object of my invention is to provide 15 a simple device for firing projectiles wherein in the gun will be automatically loaded by the movement of the gun. Another object is to provide a single operating device which will serve to move the gun into loading position and which will also serve to fire the gun. Another object of the invention is to provide a disappearing gun or one which will disappear behind or within a wall or 20 inclosure representing a fort, whereby the 25 toy will simulate disappearing guns such as are used in actual warfare. Another object of the invention is to combine both the self loading and disappearing features in a novel and simple manner.

30 In the drawings forming part of this application,

Figure 1 is an elevation of the complete device, including an inclosure representing a fort, in which view, the parts are shown in 35 the position just as the gun has been fired,

Fig. 2 is a vertical sectional view through the middle of the device showing the gun ready for firing,

Fig. 3 is a similar view with the gun in 40 loading position,

Fig. 4 is a detail sectional view of the cut off for the projectiles, being taken at right angle to Fig. 2,

Fig. 5 is a detail sectional view of the cut 45 off member,

Fig. 6 is a sectional view taken on the line 6—6 of Fig. 3, and

Fig. 7 is a sectional view taken on the line 7—7 of Fig. 2.

50 I have shown the working or movable parts arranged in or projecting from an inclosure 1 which I have designed to represent

a miniature fort. While this increases the interest in the toy, nevertheless it will be obvious that the gun may be utilized without such an inclosure. The complete combination, however, is made possible by the construction herein shown.

The inclosure 1 is here shown as a cylindrical body attached to a base 2 and having 55 a partition 3 inside and near the top of the body.

The base 2 has stamped up therefrom parallel standards 4 in which the shaft 5 is journaled, the shaft here being shown long 60 enough to avoid having to provide any means thereon for holding it in place, *i. e.*, for preventing it from sliding out of the standards 4. This facilitates disassembling 65 the parts for shipping.

70 The shaft 5 forms a support for the gun barrel 6, the shaft passing through the rear end of the latter. The inclosure 1 has an opening 7 so that the gun barrel may be swung down and through this opening to 75 project from the inclosure for firing. When the barrel swings upwardly it moves in this opening and gradually recedes into the receptacle. The gun herein shown comprises a tubular hollow body 6 adapted to receive 80 the projectiles in the muzzle, and within the gun there is shown a plunger 8 having a cap 9 to act on the projectile for projecting it. A coiled spring 10 surrounding the plunger engages at one end with the cap 9 and at the other end with a breech plate or 85 cap 11, which latter is here shown as being held in position by the shaft 5, which passes therethrough. The spring 10 is placed under compression by drawing back the plunger 90 and the power thus stored up in the spring serves to move the plunger and fire the projectile.

95 The plunger 8 extends through the breech plate 11 and it is shown provided with a hook 12 to engage the shaft 5 and terminate the forward movement of the plunger. It is also provided with an engaging portion or hook 13 with which the cocking and firing means engages.

100 There is an arm or bracket 14 here shown as fixedly attached to the rear end of the gun barrel by pins 15 and the barrel is rocked up and down by movement of this bracket.

There is a lever 16 fulcrumed to the bracket at the point 17 and one end of this lever serves as an operating handle 18. To the other end of this lever there is fulcrumed at 5 19, an operating member 20 which is shown herein as a long pawl, the lower end of which is bent at right angle to form a broad engaging part 21 to engage the hook 13 on the plunger. There is a spring 22 on the lever 16, which engages a lug 23 on the bracket 14, and this spring tends to force the lever 16 over against another lug 24 on the other side of the bracket. There is another spring 25, which is fastened to the pawl 20 and its outer end engages a lug 26 on the lever 16. The latter spring tends to force the pawl into contact with a lug 27 on the lever 16.

The lever 16 is here shown as projecting through a rear slot 28 in the member 1 so that it will be accessible for operation.

The projectiles, which may consist of balls or marbles, 29, are placed in the magazine tube 30 which projects upward from the top 3. A short tube 31 forms a continuation of 25 the tube 30 and it has a slot 32 in which part of the cut off moves. The cut off or device for allowing only one ball to drop into the barrel, is preferably operated by the barrel. It is shown herein as a member 33, which swings horizontally on a pivot 34. It consists of a horizontal part 36 which travels in the slot 32 of the tube 31. There is also a depending lip or abutment piece 37 on the member 33 and this lies in the path 35 of the end of the gun barrel. There is a spring 38, which presses on the part 37 to move the cut off device to the position shown in Fig. 2.

Operation.—Assuming that a supply of 40 projectiles has been inserted in the magazine and the gun to be in the position shown in Fig. 2, the operation will be as follows: At this time the cut off will be in the position shown in Fig. 2, and the lower ball 45 will rest on the part 33 of the cut off and the others will rest upon the first ball. At this time the open part 39 of the cut off is in line with the tube, so that the balls will rest on the part 33.

If the lever 16 is now swung downwardly, the lever, the bracket 14, the pawl 20 and the gun barrel will all move to the position shown in Fig. 3. The bracket 14 will come to rest upon the stop 40 which is stamped 55 up from the base, and this will insure the alinement of the gun barrel with the magazine tube. Just before the barrel reached the position shown in Fig. 3 it came into contact with the part 37 and it moved the 60 cut off device to the position shown in Fig. 3. When this movement of the cut off is taking place the part 36 moves between the lowermost ball and the one next above it, so as to cut off the lowermost one and support those above it. At the same time the

part 33 is moving out from under the lowermost ball and finally the latter falls into the gun barrel which, by that time, is in line with the magazine. The gun now being loaded, the lever 16 is raised (handle end) and the barrel moves down until it rests on the edge of the opening 7, which is its firing position. When the barrel begins to swing down, the cut off is caused to follow it by the spring 38. In this return 75 operation of the cut off the part 36 moves out of the path of the balls and the part 33 moves into their path, so that the support of the balls passes from the former to the latter. This completes one feeding operation 80 of the cut off. Subsequent operations take place in the same manner every time the gun swings up and back.

The first part of the upward movement of the handle 18 in the operation just described brings the barrel to rest on the lower edge of the opening or gun port 7. As the handle is moved above this position the gun ceases to move by reason of the resistance of the wall 1 and likewise the bracket 14 90 ceases to move, so the lever 16 rocks on its pivot 17 in opposition to its spring 22. During this latter movement the pawl 20 is engaged with the plunger hook 13 and the plunger is gradually pulled back or cocked, 95 as shown in dotted lines in Fig. 2. By the time the handle 18 has reached the limit of its upward movement the pawl 20 will have tripped off the hook 13. When this occurs, the plunger will be thrown forward by its spring 10 and it will throw the projectile. When the handle is released, or when it is again moved downwardly the parts will return to the full line position shown in Fig. 2, with the pawl in engagement with the 105 hook 13. The above described operations may be repeated as often as desired and the operations of loading and firing may be performed very rapidly.

It will be apparent from the above that 110 the loading operation is controlled by the gun barrel, so that the dropping of the ball occurs at the proper moment, *i. e.*, while the barrel is in line to receive it. This arrangement of the loading device is very simple 115 and effective, and it is not likely to get out of order. The device is very simple to operate because the same operating part or handle effects the loading, positioning, firing and disappearing operations. The 120 parts are few and simple to manufacture and assemble. So far as I know this is the first example of a toy disappearing gun and so far as I know it is the first toy gun which automatically receives a projectile 125 when moved to one position and which fires the projectile when moved to another position.

I have described in detail the best form 130 of the invention now known to me, but I

desire to be understood as covering all forms which come within the scope of the annexed claims.

Having described my invention, what I claim is:

1. A toy of the class described comprising a wall or inclosure, a gun movable into firing position and adapted to be retracted within or behind said wall or inclosure and common operating means for moving the gun and for firing it. 5

2. A toy of the class described, comprising a wall or inclosure, a gun movable into firing position and adapted to be retracted within or behind said wall or inclosure, a magazine for supplying projectiles when the gun is in retracted position and means for moving the gun, loading it and firing it. 15

3. A toy of the class described, comprising a wall or inclosure, a gun movable into firing position and adapted to be retracted within or behind said wall or inclosure, a magazine for supplying projectiles when the gun is in retracted position, and common operating 20 means for moving the gun and for loading and firing it. 25

4. A toy of the class described, comprising a wall having an opening or slot, a gun pivoted to swing upwardly in said opening or slot to recede within or behind the wall and to swing downwardly into firing position, a magazine for delivering projectiles to the gun when in its upward position, and means for swinging the gun and loading 30 and firing it. 35

5. A toy of the class described comprising a wall having an opening or slot, a gun pivoted to swing upwardly in said opening or slot to recede within or behind the wall 40 and to swing downwardly into firing posi-

tion, a magazine for delivering projectiles to the gun when in its upward position, and common operating means for swinging the gun, loading and firing it. 45

6. A toy of the class described comprising a magazine, a gun movable into position to receive a projectile from said magazine and movable away from the magazine for firing, and common operating means for moving, loading and firing the gun. 50

7. A toy of the class described comprising a gun movably supported, a lever having its fulcrum movable with the gun whereby said lever may move the gun and means operated by the said lever for firing the gun. 55

8. A toy of the class described comprising a gun pivotally supported, a lever having its fulcrum in fixed relation to the gun whereby said lever may swing the gun, a plunger for the gun and a pawl operated by 60 said lever for operating the plunger.

9. A toy of the class described comprising a magazine, a gun pivotally mounted to swing into and out of loading position in relation to the magazine, a lever for moving 65 the gun, a plunger for the gun and a pawl operated by said lever for operating the plunger.

10. A toy of the class described comprising a magazine, a cut off for the magazine, a gun pivotally mounted to swing into and out of loading position in relation to the magazine, said gun being arranged to operate said cut off, a lever for moving the gun, a plunger for the gun and means operated 70 by said lever for operating the plunger. 75

Signed at the city, county and State of New York, this 10th day of March, 1916.
